UNITED STATES PATENT OFFICE.

FLORIAN F. MANOR, OF OSHKOSH, WISCONSIN, ASSIGNOR TO BARTOLA MUSICAL INSTRUMENT COMPANY, OF OSHKOSH, WISCONSIN, A CORPORATION OF WISCONSIN.

MUSICAL-INSTRUMENT ELEVATOR.

Application filed May 10, 1924. Serial No. 712,312.

To all whom it may concern:

Be it known that I, FLORIAN F. MANOR, a citizen of the United States, and resident of Oshkosh, in the county of Winnebago and 5 State of Wisconsin, have invented new and useful Improvements in Musical-Instrument Elevators, of which the following is a description, reference being had to the accompanying drawings, which are a part of this 10 specification.

This invention relates to improvements in musical instrument elevators.

It is now customary to provide the orchestras of moving picture theaters and 15 other places of amusement, with organs, and it is also customary to have the different musicians give solos, and in doing so they usually stand while playing to permit the spot light to shine on them so that the audience can 20 clearly see the soloist while playing. As the organist sits down to play the organ, means have been provided for raising the instrument and the player upwardly to the height desired to be plainly seen while playing the 25 solo. Heretofore, this has been done by providing a pit beneath the platform, supporting the organ and the player, of sufficient depth to receive the elevating mechanism and driving means. The floor of theaters, 30 usually at street level, incline downwardly toward the stage and the orchestra is usually located at the lowest point and which point is so far below the street level as to negative forming a pit beneath the orchestra floor 35 due to sewer and other conduits being located just beneath the floor.

It is one of the objects of the present invention to overcome the before mentioned difficulties and provide a musical instrument 40 elevator which may be mounted on the surface of the floor with all of the elevating mechanism thereabove.

A further object of the invention is to provide a musical instrument elevator in 45 which the elevating means is not visible while the parts are in their lower position.

A further object of the invention is to provide a musical instrument elevator in which the elevator is automatically positively maintained in any position of 50 elevation.

A further object of the invention is to provide a musical instrument elevator in which the standards for supporting the

platform of the elevator in its upper position are hidden from view when the platform is in its lower position. 55

A further object of the invention is to provide a musical instrument elevator which is of simple construction, is strong and durable, and is well adapted for the purpose desired. 60

With the above and other objects in view, the invention consists of the improved musical instrument elevator and its parts and 65 combinations as set forth in the claims, and all equivalents thereof.

In the accompanying drawings in which the same reference characters indicate the same parts in all of the views. 70

Fig. 1 is a vertical sectional view taken on line 1—1 of Fig. 3;

Fig. 2 is a vertical sectional detail view taken on a larger scale;

Fig. 3 is a plan view thereof, with parts 75 removed; and

Fig. 4 is a side view on a smaller scale of the complete elevator showing an organ and seat mounted thereon.

Referring to the drawings, the numeral 80 8 indicates the floor line upon which is mounted a rectangular frame 9 preferably formed of metal approximately filled with cement or other material 10 to form a firm foundation. Socket members 11 are embedded in the four corner portions of the material and threaded standards 12 and 12' mounted therein extend upwardly therefrom. A platform 13 of about the same size as the frame 9 and through the corner portions of which the standards 12 and 12' extend, is positioned above the frame 9. Nuts 14 threaded on said standards have ball bearing connections 15 with and the platform is supported on the nuts so that when 85 the nuts are turned the platform will be raised or lowered. Said nuts are formed with integral sprocket wheels 16 which are engaged by an endless sprocket chain 17 which passes around all of the sprocket 90 wheels. The nut engaged by the shaft 12' is provided with a worm wheel 18 which is in mesh with a worm 19 mounted on the shaft of an electric motor 20. Said motor is carried by the platform 13 and the 95 threaded shafts are turned thereby. All of the standards 12 are formed with right hand threads, and the respective nuts 14 are

100 105

correspondingly threaded to cause all nuts to move in an up or down direction when turned by the shafts 12 and 12'.

To hide the standards from view, tubular posts 22 are mounted on the platform and extend over the standards, as clearly shown in Fig. 1, so that all portions of the standards which project above the platform will be hid and the posts in connection with the ropes 23 (only one being shown), will have the appearance of a guard or enclosure for the organ 24, the foot pedal case 25 and the bench 25' positioned on the platform 13.

Electric wire cables 26 extend from the motor and the organ, preferably an electric, to a source of power supply and to the organ pipe mechanism (not shown) respectively, as now in use. The current to the motor may be controlled in any manner desired.

From the foregoing description, it will be seen that the musical instrument elevator may be mounted in a very easy manner upon a flat surface with all the operating mechanism out of view of the audience of the theater in which the elevator is installed. Furthermore, the use of the threaded standards and nuts for raising and lowering the platform provides for automatically locking the platform in adjusted position, as the nuts will maintain their adjusted position under load.

What I claim as my invention is:

1. A musical instrument elevator, comprising a support, threaded standards extending upwardly therefrom, nuts threaded on said standards, a vertically movable platform mounted on said nuts, there being a relative movement between the nuts and the standards to raise and lower the platform, means carried by the platform and moving therewith for enclosing from view the portions of the standards above the platform, and means for causing said relative movement.

2. A musical instrument elevator, comprising a support adapted to be mounted upon a floor, threaded standards extending upwardly from said support, nuts threaded on said standards, a vertically movable musical instrument supporting platform mounted on said nuts, there being a relative movement between the nuts and the standards to raise and lower the platform, means carried by the platform and moving therewith for enclosing from view the portions of the standards above the platform, and means carried by said platform for causing said relative movement.

3. A musical instrument elevator, comprising a support adapted to be mounted upon a floor, threaded standards extending upwardly from said support, nuts threaded on said standards, a vertically movable musical instrument platform supported by and on which the nuts are journaled, an end-

less connection between all of the nuts, means carried by the platform and moving therewith for enclosing from view the portions of the standards above the platform, and means carried by said platform for rotating the nuts to raise or lower the platform.

4. A musical instrument elevator, comprising a support adapted to be mounted upon a floor, threaded standards extending upwardly from said support, nuts threaded on said standards and provided with sprocket wheels, a vertically movable musical instrument platform supported by and on which the nuts are journaled, means mounted on and carried by the platform for enclosing from view the portions of the standards above the platform, a sprocket chain engaging said sprocket wheels, and means carried by said platform for rotating the shafts to raise or lower the platform.

5. A musical instrument elevator, comprising upstanding threaded standards, a vertically movable musical instrument platform through the corner portions of which the standards extend, tubular posts mounted on and moving with the platform and extending around and covering the standards, nuts threaded on the standards and journaled in said platform, said nuts provided with sprocket wheels, a sprocket chain engaging the sprocket wheels, and means carried by the platform for rotating the shafts to raise or lower the platform.

6. A musical instrument elevator, comprising upstanding threaded standards, a musical instrument platform through the corner portions of which the standards extend, tubular posts mounted on the platform and covering the portions of the standards which extend upwardly through the platform, nuts threaded on said standards and provided with sprocket wheels, a sprocket chain connected to all of the sprocket wheels, a worm wheel carried by one of the nuts, and a motor carried by the platform and having a worm meshing with the worm wheel for rotating the shafts to raise or lower the platform.

7. A musical instrument elevator, comprising four upstanding threaded standards, a musical instrument platform through the corner portions of which the standards extend, tubular posts mounted on the platform and covering the portions of the standards which extend upwardly through the platform, nuts threaded on said standards and provided with sprocket chains, a worm wheel carried by one of the nuts, and a motor carried by the platform and having a worm which is in mesh with the worm wheel for rotating the shafts to raise or lower the platform.

In testimony whereof I affix my signature.
FLORIAN F. MANOR.
